UNITED STATES PATENT OFFICE.

HENRY HENDERSON, OF NEW YORK, N. Y.

MOLD-RAMMING APPARATUS.

No. 876,054.

Specification of Letters Patent.

Patented Jan. 7, 1908.

Application filed April 17, 1907. Serial No. 368,779.

To all whom it may concern:

Be it known that I, HENRY HENDERSON, a citizen of the United States, residing in the borough of Manhattan, city, county, and 5 State of New York, have invented a certain Improved Mold - Ramming Apparatus, of which the following is a specification.

This invention relates to apparatus for ramming molds for cylindrical castings— such as pipe. The rammers are power driven and are so mounted as to be adjustable vertically and horizontally, and are carried by a support that swivels about a vertical axis, being suspended flexibly therefrom out 15 of line with said axis. The apparatus may be used with stationary or rotatable molds. By the vertical and horizontal adjustments the rammers may be readily adjusted to molds of different diameter and arrangement. The swiveling support permits the pendent rammers to be brought into proper relation to the mold—as, for instance, if the 20 axis of the support coincides with the axis of the mold the radius of the points of suspension of the rammers may be substantially the radius of the mold. This construction permits of the employment of a plurality of rammers suspended from a single support.

30 In the accompanying drawings which show one form in which this invention may be embodied: Figure 1 is a general elevation partly in section and partly broken away for convenience of illustration upon one sheet: Fig. 2, a vertical section through a flexibly supported swiveling rammer cylinder support: and Fig. 3, a detail sectional view showing the end of a rammer cylinder, the rammer shaft and bit and a guide sleeve 40 or tube surrounding the shaft and attached to the lower head of the cylinder.

A column is properly supported upon a suitable foundation, to be detachable therefrom for transportation if desired. It is 45 composed of a portion *a* and a rotatable upper portion *b* turning upon balls *c* running in an annular race-way between the two sections of the column. The upper end of the part *b* carries a horizontal frame *d* provided with tracks or ways upon which runs a small truck *e* to which is connected a rope *f* passing over an idler on a bracket at the end of the horizontal frame and thence back over another idler pulley adjacent the column 55 from whence it extends downwardly, its lower end being provided, if desired, with a

chain and equipped with a suitable ring *f'* adapted to be engaged with a projection or catch *g* on the side of the column.

h is a pipe extending up along the side of the column and adapted to be connected at its bottom with a source of fluid under pressure. At *h'* it is provided with a suitable hand controlling-valve and at the top its turned over end is coupled to a length of 60 flexible armored hose *i* which passes under a pulley to which is attached a counter weight *i'*, thence up over a pulley *i''* at one end of the horizontal frame *b*, thence over a grooved wheel forming part of the movable 70 truck *e* and thence downwardly, its end being connected to a swiveling rammer supporting apparatus that may be conveniently constructed as presently described. The parts are so counter-weighted that there is 75 a slight tendency of the truck *e* to run inwardly and it may be drawn outwardly or away from the axis of the column and secured in position by the rope or cable *f*.

The rammer supporting apparatus, indicated generally by the letter *J* in Fig. 1, may be composed of a horizontally divided casting *j*, the sections of which are held together by bolts. The upper section has a tubular extension *j'* tapped at its upper end and formed 80 with a lateral extension *j''* tapped at its outer end and shown in Fig. 2 as closed by a screw plug. The lower section has a tubular extension *j'*, the axis of which is coincident with that of the tubular extension *j'*. In a 85 cylindrical chamber between the two sections *j*, *j'* of the casting and supported upon anti-friction balls *j'* is a flat cylindrical body *k* having from its under face a tubular extension *k'* extending into the enlarged lower end 95 of the part *j'*. This tubular extension connects with another tubular extension *k''* extending from the bottom of *k* through the tubular extension *j''* on the lower section *j* of the casting. The lower end of *k''* is tapped 100 to receive the threaded end of one branch of a T-coupling *m*, the other ends of which are tapped. A flexible ring valve *n* is applied to the upper end of *k'* in such way as to seal the joint between it and the part *j'* when a 105 compressed fluid is introduced. The upper face of the cylindrical body *k* has formed in it an annular channel for the reception of a packing ring *n'* which runs in contact with the under face of the upper section *j* of the 110 inclosing casting. One branch of the T-coupling *m* has screwed into it a rod or length of

pipe o on which is fitted to slide an adjustable counter weight o' and to the end of which is attached a supporting link o^2 attached at its upper end to a plate o^3 turning about the part j' . To the other branch m' of the T-coupling is connected a short length of flexible hose p which runs over a curved supporting piece or shoe q bolted to the body of the T-coupling and supported by links q' attached at their upper ends to the swiveling plate o^3 . The shoe q may be adjusted being provided with a series of bolt-holes p' . This permits of adjustment of the radius of the point of suspension of the rammer with reference to the axis 15 of the swiveling support J .

Attached to the downwardly extending end of the section p of armored hose is a double acting power cylinder r , the piston of which is adapted to be reciprocated by fluid 20 under pressure, such as compressed air, supplied through i , j' , and p and to the piston of which is attached a rammer shaft s provided with an inclosing, guiding and manipulating sleeve or tube t secured to the lower head of the cylinder r . The rammer shaft s at its lower end is provided with a bit or rammer head s' which is removably attached thereto as indicated in Fig. 3. Compressed air supplied at the bottom of the pipe h may be controlled in its admission to the armored hose i which supplies it to the swiveling support J and cylinder r to reciprocate its piston and attached rammer s , s' . The rammer cylinder is flexibly supported by the piece of armored hose p and by the armored hose i that is coupled with the upper end of the tubular extension j' of the swiveling rammer supporting apparatus. The rammer cylinder has adjustment around the axis of the 40 supporting column; radially thereto; about the axis of its swiveling support; and vertically. When the tubular guide t surrounding the rammer shaft is grasped by the workman, the rammer bit may be 45 properly directed to the desired point and repeated blows, as may be desired, delivered upon the sand in the mold. If the mold be stationary, all parts of it may be reached by the described adjustment of the apparatus; or, if the mold be rotary, the ramming cylinder may be given the desired radial adjustment and ramming of the mold, as it rotates, be effectively accomplished. Near the base of the column is provided a 55 platform u upon which the workman may stand, and which may be provided with a sliding or adjustable bifurcated guide piece u' for the rammer shaft.

The weight o' may be radially adjusted to 60 counter balance the rammer cylinder r . The weight i may be such that the truck e may be readily controlled by cable s , and the rammer cylinder raised and lowered by strain exerted by the workman either directly upon 65 the rammer shaft or upon the guide tube t .

surrounding it. The tube is preferably employed in all cases. The drawing shows a pipe mold mounted upon a revolving platform, rotation of which is produced by any suitable power as a motor v , driving a pinion 70 running in a rack on the rotating platform v' .

This invention is shown embodied in a form deemed to be practicable and efficient but obviously it may be embodied in other organizations without departing from the 75 principles of construction and mode of operation herein disclosed.

I claim:

1. Mold ramming apparatus comprising a support swiveling about a vertical axis, 80 a power device suspended therefrom at a point out of line with said axis, and a rammer shaft reciprocated by the power device.

2. Mold ramming apparatus comprising a support swiveling about a vertical axis, a power device suspended therefrom at a point out of line with said axis, a rammer shaft reciprocated by the power device and means for adjusting such point of suspension relatively to said axis. 90

3. Mold ramming apparatus comprising a vertically and horizontally adjustable support swiveling about a vertical axis, a power device suspended therefrom at a point out of line with said axis, and a rammer shaft 95 reciprocated by the power device.

4. Mold ramming apparatus comprising a vertically and horizontally adjustable support swiveling about a vertical axis, a power device suspended therefrom at a point out of 100 line with said axis, a rammer shaft reciprocated by the power device and means for adjusting such point of suspension relatively to said axis.

5. Mold ramming apparatus comprising 105 a flexibly suspended support swiveling about a vertical axis, a power device flexibly suspended therefrom at a point out of line with said axis, and a rammer shaft reciprocated by the power device. 110

6. Mold ramming apparatus comprising a flexibly suspended support swiveling about a vertical axis, a power device flexibly suspended therefrom at a point out of line with said axis, a rammer shaft reciprocated by the power device and means for adjusting such point of suspension relatively to said axis. 115

7. Mold ramming apparatus comprising a flexible tube for supplying a fluid under pressure, a hollow part connected with the 120 tube and suspended thereby, a hollow part swiveling on the first named part and communicating therewith, a flexible tube communicating with such swiveling part, a power cylinder suspended from said last 125 named tube and supplied with fluid under pressure from it, and a rammer shaft reciprocated by the cylinder.

8. Mold ramming apparatus comprising a vertically disposed rammer shaft, a flexibly 130

supported power device actuating and supporting the rammer shaft, means whereby the power device may be adjusted circumferentially about a vertical axis, radially 5 with reference to said axis and vertically with reference to the mold.

9. In a mold ramming apparatus, a vertically disposed rammer shaft, a power device supporting it and operating to reciprocate it vertically, a swiveling support for the power device about the axis of which it may be rotated, means for flexibly suspending the swiveling support and means whereby such support may be adjusted circumferentially about a vertical axis, radially with 10 reference to said axis and vertically with reference to the mold.

10. Mold ramming apparatus comprising

a supporting column formed in two sections, the upper one of which is rotatable, a horizontal frame carried by the upper portion of the column, a truck traveling on the frame, means for moving the truck back and forth on the frame, a counter weighted compressed air supply hose passing downwardly 20 from the truck, a swiveling power cylinder support suspended from the hose, a power cylinder carried thereby and a rammer shaft reciprocated by its piston.

In testimony whereof, I have hereunto 25 subscribed my name.

HENRY HENDERSON
